Philip D. McLean ATTORNEY

UNITED STATES PATENT OFFICE.

JOSEPH BURGER, OF BROOKLYN, NEW YORK.

MANUFACTURE OF WOODEN HEELS.

Application filed November 17, 1927. Serial No. 233,931.

This invention relates to the manufacture of wooden heels and has the special objects in view of facilitating and increasing production, simplifying operations and generally improving the art.

Important novel features of the invention are a special process by which two or a greater number of heels may be produced in the same time and with substantially the same machinery as has heretofore been required for the manufacture of a single heel, the special preparation of the rough material to enable such increased production and the special cutter mechanism to operate on the material so provided.

These and other important features of the invention will appear more fully as the specification proceeds.

The drawing accompanying and forming part of the following specification illustrates the method and special means by which the same is effected and as the same is primarily for purposes of disclosure, it will be understood that certain modifications and changes may be resorted to without departure from the true spirit and scope of the invention as hereinafter described and broadly claimed.

Figure 1 is a broken perspective view illustrating the lumber as it is compounded and then cut up into multiple unit blocks.

Figure 2 is a perspective view illustrating one of the multiple unit blocks as it is grooved for the breast side of the heel.

Figure 3 is a broken side elevation, showing the grooved double block as held in the jack and acted on by a double cutter to simultaneously turn two of the heels from one of these double unit blocks.

Figure 4 is a perspective view illustrating the two heels thus simultaneously produced.

Figure 5 is a broken perspective view illustrating a method of temporarily joining the strips of heel lumber by adhesive applied along the meeting edges of the strips.

Figures 1 and 5 illustrate what may be considered the initial stages of the process; that is, the securing of the strips of heel material together to enable the simultaneous production of a number of heels. In the cases illustrated, two such strips or bars of

heel lumber are shown at 7, 8, overlaid in coextensive relation and secured together in this fashion, in the first instance, by tapes 9 of adhesive material, such as paper or the like, and in the second instance, by lines of 55 glue or other adhesive 10.

In both these constructions, the wooden strips are secured together only along their outer edge portions, so that upon the cutting away of such outer edge portions, the members will be automatically freed from each other.

The compound lumber, made up of two or more strips thus temporarily secured together, forms a unit which can be handled 65 as a solid piece.

In the present practice of the invention, the compound strip is first cut on diagonal lines 11 of the proper inclination into heel blocks 12, as in Figure 1. These heel blocks 70 are then grooved across one end, as indicated in Figure 2 at 13, to provide the breast faces of the two or more heels.

These grooved blocks held together at their edges, as indicated in Figure 2, are next 75 secured in the clamp 14 of the jack 15, as indicated in Figure 3, and the two or more blocks are carried still as a single unit to the cutter, which as shown, has two or as many cutting edges 16 as there are individual 80 blocks in the composite block unit. This cutter is preferably of the single spindle type covered in patents 1,595,975 and 1,595,976, so that with the carrying of the jack up to the cutter spindle, both, or if there be more than 85 two, all the several heel pieces will be turned at once.

Figure 3 illustrates the parts of such a single spindle machine in which the single vertical spindle is shown at 17 and in which the jack is shown as having been brought up to the cutter blades and turned about half way to face the first side and extend the cut part way about the back of the heel pieces, and it will be understood that the further rotative movement of the jack will extend the cuts made by these blades across the backs of the individual heels, around the opposite sides of the blocks to the far breast corners.

In making these cuts, the joined edge portions of the block layers are cut away as will be clear from Figure 3, so that when the jack is withdrawn and the clamp is loosened, 5 the two completed heels will of themselves fall apart without requiring any separating action on the part of the operator.

The cutting blades are shaped with the necessary number of sections to cut the number of heel layers held in the jack and these 10 cutting sections may be exact duplicates to simultaneously produce a number of duplicate heels, or if desired, these cutting sections may vary so as to produce in one and 15 the same operation, heels of different shapes or sizes. In the particular construction shown, the upper cutting section 16 is shouldered back at its lower end at 18 adjacent the upper end of the lower cutting section 16, so as to enable the latter to enter beneath the flat face of the upper heel piece. Two of the completed heels simultaneously produced by these operations are indicated 20 at 19 in Figure 4, shown as they fall apart at 25 in their removal from the jack.

While, because of the saving of time and other advantages, it is preferred to turn the heels in the single spindle machines of the 30 patents above enumerated, it will be clear that the invention may be used with advantage in the ordinary commercial types of 35 double spindle heel turning machines.

The strips of heel lumber may be fastened together and kept in stock in that relation 35 and then sawed into blocks, grooved and turned as required. This particular method, if used, has the advantage of giving the glue or other securing agent, plenty of time to 40 set and harden before the material is subjected to the strains of sawing, grooving and turning, but it is not intended that the invention be limited to such a timing of the steps as different modes of fastening and other elements may vary the procedure more 45 or less. The layers of heel stock are of the proper thickness and are held in the jack so that each layer will accurately meet the sections of the blades designed to cut a heel 50 out of that particular layer. The layers may be put together in long lengths of the stock and this operation may be economically and rapidly performed by automatic machinery so that the cost of thus preparing the stock is but a small item as compared to the 55 advantages of simplified handling and increased production.

What is claimed is:

1. The method of manufacturing wooden heels which comprises securing together two 60 or more layers of wood heel stock in coextensive face to face relation and then turning said compound multiple layer stock with a cutter having two or more complete heel turning edges alined respectively with the

individual layers of the compound multiple 65 layer wood heel stock.

2. The method of manufacturing wooden heels which comprises securing together in juxtaposed relation two or more wood heel blocks and then simultaneously turning all 70 of said wood heel blocks while so held in such juxtaposed relation and with a cutter having a number of complete wood heel turning edges registered respectively with the individual heel blocks. 75

3. The method of manufacturing wooden heels which comprises securing together at their meeting edges only two or more wood heel blocks arranged in juxtaposed relation and then simultaneously turning the two or 80 more blocks while thus held with a cutter having complete wood heel turning edges one for each block and arranged to trim away the secured edge portions of the blocks 85 in the turning operation. 90

4. The method of manufacturing wooden heels which comprises securing separate lengths of wood heel stock in juxtaposed relation, cutting the multiple layer compound stock so produced on inclined lines to form 90 units each consisting of superposed wood heel blocks having inclined end faces and then turning the compound units so produced with a cutter having a complete wood heel turning edge for and registered with 95 each of such heel blocks.

5. The method of manufacturing wooden heels which comprises holding two or more wood heel blocks in face to face relation, simultaneously grooving the ends of the several blocks while so held to form the breast faces on said heel blocks and then simultaneously turning all of said blocks while thus held with a cutter having a cutting edge for and registered with each of said heel blocks. 100

6. The method of manufacturing wooden heels, which comprises holding a number of wood heel blocks in superposed relation and operating on said superposed heel blocks 110 while so held with a cutter having superposed cutting edges relatively positioned each to register with one of the thus held heel blocks.

7. The method of manufacturing wooden 115 heels which comprises holding a number of angled wood heel blocks in superposed relation and turning said angled wood heel blocks while so held with a cutter having plural wood heel turning edges arranged 120 each edge in alinement with one of said angled wood heel blocks.

8. Apparatus for simultaneously turning a plurality of wooden heels comprising a jack for holding a plurality of superposed 125 wood heel blocks and a cutter having a plurality of wood heel turning edges in superposed relation arranged to register

each with one of the heel blocks held in the jack.

9. Apparatus for simultaneously turning a plurality of wooden heels comprising a 5 jack for holding a plurality of superposed wood heel blocks and a cutter having a plurality of wood heel turning edges in superposed relation arranged to register

each with one of the heel blocks held in the jack, said cutter being shouldered between 10 the adjoining heel turning edges to enable each edge to turn a heel without conflicting with the turning of the next adjacent heel.

In testimony whereof I affix my signature.

JOSEPH BURGER.
